UNITED STATES PATENT OFFICE.

ANTON M. LEGRAND, OF MILWAUKEE, OREGON.

NON-REFILLABLE BOTTLE.

SPECIFICATION forming part of Letters Patent No. 608,879, dated August 9, 1898.

Application filed May 28, 1897. Serial No. 638,615. (No model.)

To all whom it may concern.

Be it known that I, ANTON M. LEGRAND, of Milwaukee, in the county of Clackamas and State of Oregon, have invented certain new and useful Improvements in Non-Refillable Bottles; and I do hereby declare the following to be a full, clear, and exact description of the invention, such as will enable others skilled in the art to which it appertains to make and use the same.

My invention relates to non-refillable bottles.

My object is to provide a non-refillable bottle of simple and cheap construction which can be readily filled and sealed and the contents thereof removed at any time, but which, owing to its peculiar construction, cannot be refilled without detection.

Having the foregoing object in view, the invention consists of a non-refillable bottle comprising certain improved features and novel combinations of parts appearing more fully hereinafter.

In the accompanying drawings, Figure 1 is a sectional elevation, and Fig. 2 a perspective detail view, of the stopper.

The numeral 1 designates the body of the bottle, and 2 the neck thereof, which is provided with an inner annular ledge or shoulder 3 in its lower portion and has an upper inner annular groove 4. The body of my improved stopper is shown at 5, the same being in the form of a casing, and within this casing there is located a compound curved spring 6, having catch-pins 7 secured to its ends and projecting through the sides of the casing, said pins having shoulders 8 to limit their outward movement. These pins are adapted for reception in the annular groove 4. The numerals 9 and 10 designate legs which extend downwardly from said body or casing. There is a ring 11 secured to the lower ends of said legs, the same being provided with notches 12 in its periphery. The numeral 13 designates an interfering-disk which is secured to the top of the casing and is provided with perforations. There is a disk valve 15, which is of slightly less diameter than the neck and lies on the shoulder 3, but is adapted for movement between said shoulder and the ring. It will be observed that the stopper is tapered from top to bottom, and the neck is of similar

shape inside. An ordinary stopper 16 can be employed in the upper end of the neck.

After the bottle has been filled the disk valve is placed on its seat. The locking-stopper is then pushed down into the neck, and immediately upon the catch-pins coming in alinement with the annular groove the said pins are forced outwardly by the spring and into the groove, thereby securely locking the stopper in position. The ring will then lie somewhat above the disk valve, so as to permit free tilting movement of the same. The ordinary stopper can then be placed in the bottle to securely cork the same. When it is desirable to obtain any part or the whole of the contents of the bottle, the ordinary cork stopper is removed and the bottle tilted. The fluid lifts the disk valve from its seat and passes through the ring and the notches in the periphery thereof and out through the perforations in the interfering-disk. Immediately upon the bottle being placed in an upright position the disk valve drops back to its seat, and should an attempt be made to force fluid into the said bottle said valve will be urged against its seat and the fraud cannot be accomplished. The stopper is locked securely in the neck, and it will be necessary to break the interfering-disk if refilling is to be had. The interfering-disk prevents any instrument from being inserted to lift the disk valve from off its seat.

It is preferable to make the parts of glass, so that no chemical action will be set up in the fluid contained in the bottle. There are many slight changes which could be resorted to in carrying out my ideas without detracting from any of the advantages of the device, and hence I reserve to myself the right to make all such changes as come within the spirit and scope of the invention.

Having thus described my invention, what I claim as new, and desire to secure by Letters Patent, is—

1. In a non-refillable bottle, the combination with a bottle-neck having inner recesses or pockets and an annular ledge or shoulder below said pockets of a locking-stopper comprising a body or casing of less size than the neck, spring-actuated catch-pins carried by said casing and adapted for reception in the pockets, an upper perforated interfering-disk

secured to the casing, a lower ring having side openings therethrough, said ring and disk being adapted to fit the neck of the bottle, and a disk valve located between said 5 ring and the annular ledge in the neck of the bottle, substantially as described.

2. In a non-refillable bottle, the combination with a bottle-neck provided with inner pockets or recesses, of a locking-stopper comprising a body or casing of less size than the neck, spring-actuated catch-pins carried by said casing and adapted to engage with said pockets, a perforated interfering-disk secured to said casing, legs depending from the cas-

ing, a ring secured to said legs and provided 15 with notches in its periphery, the aforesaid interfering-disk and ring fitting the neck of the bottle, and a disk valve seated on a shoulder in the neck and whose movement is limited by the aforesaid ring. 20

In testimony whereof I have signed this specification in the presence of two subscribing witnesses.

A. M. LEGRAND.
